UNITED STATES PATENT OFFICE.

FREDERICK C. LAVARACK, OF MONTCLAIR, NEW JERSEY, AND WILLIAM M. PAGE, OF PITTSBURGH, PENNSYLVANIA.

RAIL BOND.

Application filed January 15, 1923. Serial No. 612,619.

This invention relates to electrical conductors, especially to connectors, and more particularly to rail bonds.

At the present time most of the important 5 railways are somewhat extensively equipped with automatic signals and related devices which seem to be best controlled at the present time by what is known as a track circuit. This track circuit includes a section 10 of the rails electrically insulated from adjacent sections, a relay or translating device connected across the rails at one end of the section and a battery or other source of a difference of potential connected across 15 the rails at the other end. The abutting ends of the usual thirty foot rail length within the section are connected as usual with fish plates which usually furnish a metallic path from one rail length to the 20 adjoining rail length even if the ends of the rails are not in actual contact. It has been found, however, that the metallic path for 25 the flow of electricity from one rail to an adjoining rail is not of sufficiently low resistance when entire dependence for a metallic path between rails is placed upon the usual mechanical connection between rails, consequently all installation of track circuits also include a special connector or rail 30 bond between the adjacent rail ends within the section, for supplying a proper low resistance path for the flow of electricity from rail end to rail end.

Heretofore the connectors or rail bonds 35 have been of many types, some electrically or gas welded to the respective rail ends, some connected by channel pins and some by what are known as plugs.

Applicants' invention relates to the plug 40 type of rail connector or bond.

The principal object of applicants' invention is the production of a plug bond in which the electrical connection between 45 plugs will be obtained by the same means by which the mechanical connection is obtained.

A further object of applicants' invention is the production of a connection between 50 the plugs and connecting wire in a plug type of bond which will effectively eliminate corrosion at this point.

A further object of applicants' invention is the production of a joint between the 55 plugs and connecting wires in a plug type of bond which will be of a nature especially

adapted to that type of plug bond in which a plurality of wires extend between the plugs.

A further object of applicants' invention 60 is the production of a bond of the type specified in which the union between the wires proper and the bond will be of unusual mechanical strength.

A further object of applicants' invention 65 is the production of a bond of the type specified in which the electrical union between the plugs and the wires proper will be so exceptionally intimate and so formed as to be of relatively high conductivity.

Other objects and advantages will appear 70 as the description of the preferred physical embodiment and modification thereof, selected to illustrate the invention, progresses and the novel features of the invention will be particularly pointed out in the appended 75 claims.

In describing the invention in detail and the particular preferred physical embodiment and desirable modifications thereof selected to illustrate the invention reference 80 will be had to the accompanying drawing illustrating a preferred physical embodiment of the invention and desirable modifications thereof, and in which:

Figure 1 illustrates the abutting ends of 85 two rails connected by applicants' improved bond; Fig. 2, illustrates the manner of beginning the construction of the joint between the plug proper and the wires proper; Fig. 3, illustrates further progress in constructing the joint shown by Fig. 2; Fig. 4, shows the completed joint as shown started in Fig. 2; Fig. 5, is an enlarged cross-sectional view of Fig. 4; Fig. 6, illustrates one end and an intermediate portion of the 90 completed bond; Fig. 7, illustrates the completed form of the joint between the plug and wires when three wires are used between 95 plugs; Fig. 8, shows the plug and adjacent wire portion of a different type of three 100 wire bond; Fig. 9, is a cross sectional view on the plane indicated by the line IX-IX of Fig. 8.

In Fig. 1 are shown rails 1 and 2 held together mechanically by the usual fish plate 105 3 and bolts 4.

Applicants' improved bond in Fig. 1, is designated as a whole by B and consists generally of one or a plurality of connecting wires 5 attached at each end to a plug 6 110

which is driven into a cavity formed in the web 7 of the rails.

By reference to Fig. 2 it will be seen that plug 6 is formed with a bore 8, through which extend the wires 5.

In order to form our type of joint between wires 5 and plug 6 we also thread through bore 8 the wrapping wire 9 so that a considerable portion thereof extends beyond each side of the plug 6. The wire 9 is wrapped closely about the wires 5 and close to the sides of plug 6, as shown in Fig. 3, and when the wrapping is complete the joint appears as shown in Fig. 4.

After the joint is completely wrapped as shown by Fig. 4, it is suitably treated in accordance with well known art and dipped in a molten metal or alloy preferably tin. When the joint cools all parts are firmly cemented together by tin 10 as appears in Fig. 5. This tin will firmly fasten the wires 5 together and to the plug 6 and unite wrapping wire 9 with the rest of the structure and in particular wrapping wire 9 will be firmly united to wires 5 and plug 6 at the sides of plug 6, that is at the point 11.

Fig. 6 illustrates one end and an intermediate portion of the completed bond and shows the intermediate tie wires 12 which are wrapped about the wires 5 and serve to keep them together.

Fig. 7 illustrates a completed joint employing three wires 5.

Fig. 8 illustrates a completed joint employing three wires 5, and these wires are not inserted in plug 6 in what may be called a single bore, but as shown by Fig. 9, three bores 13, 14 and 15 are formed, which are merged one into the other, by a central bore 16. Each of the larger bores receives one strand of wire 5 while the central bore receives wrapping wire 9.

The wrapping wire 9 shown in the several joints firmly mechanically ties wires 5 to the plug 8 and so supports wires 5 that the inevitable vibration of the wires does not cause them to break just inside of the head of the plug 6. This supporting action is augmented by the tinning which being relatively soft really affords a sort of resilient connection between plug 6 and wires 5 so that the inevitable vibration of wires 5 are damped and absorbed by the interposed tin, so that due to the wrapping wire 9 and the tin 10 no defi-

nite plane of vibration exists in wires 5 adjacent the head of plug 6.

The tin also serves the further function of appropriately electrically connecting wires 5 and plug 6 and the further important function of completely excluding moisture from the joint thereby preventing corrosion and with resultant increased resistance and mechanical weakening.

Although we have described a preferred physical embodiment of our invention and desirable modifications thereof, nevertheless we desire to have it understood that the forms selected are merely illustrative and do not exhaust all of the possible physical embodiments of the idea of means underlying our invention.

What we claim as new and desire to secure by Letters Patent of the United States is:

1. The method of forming the connection between a plug and the wires proper in a plug type rail bond which consists in forming an orifice in the head of the plug at a right angle to the longitudinal axis of the plug, positioning the wires proper, in the orifice so that a relatively slight portion thereof protrudes, then passing a relatively short length of wrapping wire through the orifice so that either end protrudes beyond the sides of the plug, then wrapping the protruding ends of the wrapping wire tightly about the first mentioned wires and against the sides of the plug then cleaning and fluxing all parts adjacent to plug and then dipping the joints so made into a molten metal of relatively low melting point.

2. In a rail bond, in combination: two plugs each formed with an orifice therein at right angles to the longitudinal axes thereof; a plurality of wires extending from one plug to the other plug and having their ends extending into and through the orifices in the plugs; wrapping wires, one positioned in each orifice and having its ends extending beyond the sides of the plug and wrapped tightly around the wires and tightly against the sides of the plugs; a relatively low melting point metal filling all of the interstices between the several wires and the plugs and means intermediate the plugs for keeping the first mentioned wires closely together.

FREDERICK C. LAVARACK.
WILLIAM M. PAGE.
